ELECTRIC SWITCH

Frederick Von Voigtlander, Ann Arbor, Mich., assignor, by mesne assignments, to Sperti Faraday Inc., a corporation of Ohio

Application January 3, 1947, Serial No. 720,801

4 Claims. (Cl. 200—159)

1
This invention relates to features of simplicity and economy in electric switch constructions, more particularly of the push button type.

This invention has utility when incorporated in a unit adapted to be thrust into a cylindrical socket in thereby installing in a desired position for use. The unit main insulation body has a central key socket for the push element, at normally outward switch open position. A drive screw assembles the push button element in the body with a helical compression spring about the screw. A push on the button element or plunger closes the switch circuit at spring arms from a pair of spaced terminals. A yieldable finger-carrying shell about the body holds the body in a mounting socket therefor. The terminals, arms, an insulation mounting and the shell are assembled by two-self-tapping screws thru the respective terminals. The inter-relation of these parts contributes to a sturdy, compact efficient switch.

Referring to the drawings:

Fig. 1 is a plan view, with parts broken away, of an embodiment of the invention in a normally-open type of push button switch, the broken away portion showing the key means for holding the button from turning or rotating relatively to the body;

Fig. 2 is a side view, with the major portion in vertical section, showing the assembled parts and the switch features in the normal or open switch position therefor;

Fig. 3 is a view in bottom plan of the push button switch unit of Fig. 1, with one of the terminals removed, thereby to expose fully one of the spring arms of the switch;

Fig. 4 is another bottom plan view of the unit, with the spring arms, as well as the terminals, removed, and a portion of the insulation disk also omitted to expose the spring fingers of the friction lock or socket providing the holding means for locating the insulation body of the unit in installed position for use; and

Fig. 5 is a fragmentary bottom plan view of the main body or insulation housing of the device or unit.

A main member or plastic body 1 has a major cylindrical exterior portion 2, upward to a slight overhang 3, as a rim or flange. The rim 3 bounds a recess or concentric chamber 4 having a pair of diametrically disposed key lugs 5. The chamber 4 has a bottom 6 with a concentric, slightly greater depth portion 7, to provide a seat for helical compression spring 8. The spring 8 is about a drive screw 9 which is freely slid-

2
able thru an opening 10 from the bottom of the chamber 4.
With a head 11 of the screw 9 seated against a central inward offset from a bottom face 12 of the body 1, it is normally so retained by the action of the spring 8, for the screw 9, as thru the spring 8, is drive anchored in a central boss 13 depending from a push button 14, also preferably of plastic material. Before thrusting the screw 9 into an axial recess in the boss 13, an eyelet or sleeve 14' is press fitted thereabout as a reinforcement for the plastic element 14. Outside the region of the spring 8 in its contact with the underside of the push button 14, the button 14 has arc-shaped recesses or outwardly open grooves 15 adapted to have slide register clearance about the key lugs 5 in push button operation. Depressing of the button 14 against the action of the spring 8 is limited by the lower or free ends of these inwardly arced or channel portions 15 striking the bottom 6.

The bottom 12 of the body 1, besides thru the opening 10, has a pair of screw openings 16 (Fig. 5). Self-tapping screws 17 thru terminals 18, spring arms 19, insulation disk 20, into the openings 16 in the body 1, thereby clamp inward overhang portions 21 between the disk 20 and the bottom 12. The lesser pitch for the screws 17, than for the screw 9, involves less installing strain upon the body 1 and is reliable for maintaining assembly. The overhang 21 has clearance regions 22 for adequate spacing bounds about the screws 17, thereby to maintain insulation relation from yieldable holding fingers 23 in partial seats 24 of the body side 2 in their extent toward the rim 3.

The insulation disk 20 in its clamp direction toward the bottom face 12 of the body 1, engages the rim 21, but is spaced from the screws 17 sufficiently to avoid current leakage to the fingers 23, affording the anchorage as thrust into a socket in locating the unit in position for use.

Primarily the unit comprises the plastic housing or body 1 and the plastic push button 14, each of insulation material. There is a third insulation element, the disk 20. The reinforcing sleeve or eyelet 14' in the spring chamber is not in circuit relation with the stem 9. This chamber above the floor 7 is a non-electric current region. While the stem 9 extends thru this floor, its electric current effective region is at its head 11 for current flow between the arms 19 of the respective terminals. The screws 17 which assemble the terminals 18 with the body 1 are clear

of the shell 21, 23, for the rim 21 does not extend sufficiently inward under the disk 20 to engage the screws 17.

The insulation disk 20 locates the spring arms 19 of the terminals in such proximity to the screw head 11 that the slide travel of the screw 9 thru the opening 10 contacts and slightly bows the spring arms 19 and forms a short circuit bridge at the normal clearance 25 before the stops 15 strike the bottom 4. The disk 20 has openings 26 for the self-tapping screws 17, and adjacent thereto openings 27 for key prongs 28 of the terminals 18 to anchor the terminals against turning as to the body 1. Completion of the anchoring is due to recesses 29 in the face 12 adjacent the openings 16. With the terminal 18 seated about the screw 17, against the spring arm 19, the terminal prong 28 enters the opening 27 in a recess or seat 29. Each of the spring arms 19 has an opening 30 for a self-tapping screw 17 mounting the terminal 18 therewith, so that the key or prong 28 projects thru an opening 31 in the arm 19 to engage with a seat 29 in the face of the body 1, completing the anchoring against turning as to the body 1.

When formed of plastic, the molded plastic body 1, is in association with the complementarily molded plastic plunger 13, 14, forming the major structure and all insulation material.

The unit is readily adapted to assembly line production. The several parts are nested. A press operation may thrust the main screw 9 into the assembly with the button head 14, prior to the placing of the terminals 18 with their spring arms 19, the clamp insulation disk 20 against the rim of the finger-shell 21, 23, for the self-tapping screws 17 to complete the unit.

What is claimed and it is desired to secure by Letters Patent is:

1. An electric switch insulation body adapted to be thrust into a socket to determine in-use location therefor, an insulation disk, said body being embraced by an annular series of yieldable frictional holding fingers, there being an inward overhang mounting rim for the fingers, a pair of switch terminals, and switch terminal mounting means clamping the disk and overhang with the body for directly assembling the fingers with the body.

2. An electric switch insulation body, an annular series of relatively yieldable spring fingers embracing the body connected by a rim over an end of the body, an insulation disk against the rim, and holding means extending thru the disk and clear of the rim into the body for assembling the fingers with the body.

3. An electric switch insulation cup body having an outward annular rim, said cup interior having key configuration, electric switch terminals connected to the body bottom, an insulation plunger insertable in the cup of the body and having complementary key configuration to that of the cup for holding the plunger and body against relative rotation during relative reciprocation, and switch terminal closing means mounted on the plunger and spaced from the insulation key configurations.

4. An electric switch of the push button type embodying an insulation body with an open top and a wall extending therefrom to form a chamber with an inwardly extending bottom flange having an opening therethru concentric with the open top, said top having an outwardly extending integral flange parallel with the bottom flange and adapted to form a limit stop upon insertion of the body in a mounting opening therefor, an insulation push member closure for the open top, said member having an insulation extension boss into the chamber of less diameter than the closure, a switch-closing conductor head having an integral stem slidable thru the opening in the bottom flange and extending into the chamber to engage the extension boss, a compression helical spring embracing the boss and thereby insulation spaced from the stem, said spring in its extent between the chamber-exposed sides of the push member and bottom flange urging the head against the outside of the bottom flange, and independent oppositely directed conductor arms assembled with the body flange outwardly from the chamber, said arms being disposed normally clear of the head and approximately parallel to the bottom flange, whereby thrusting of the push member may move the head to close a switch circuit between said arms.
